UNITED STATES PATENT OFFICE

AMOS MORIN, OF DANIELSON, CONNECTICUT, ASSIGNOR TO VICTOR RING TRAVELER COMPANY, OF PROVIDENCE, RHODE ISLAND, A CORPORATION OF RHODE ISLAND

TRAVELER FOR TWISTING MACHINES

Application filed January 12, 1928. Serial No. 246,327.

This invention relates to an improved construction of ring traveler more particularly adapted for use in twisting machines and an object of this invention is to so construct a traveler of this character that it will be balanced to hang vertically on the ring and yarn and therefore will float more freely and not cramp on the ring when rapidly revolved about the package on which the yarn is being wound.

With these and other objects in view, the invention consists of certain novel features of construction, as will be more fully described, and particularly pointed out in the appended claims.

In the accompanying drawings:

Figure 1 is a perspective view showing my improved traveler as mounted on a vertical twisting ring.

Figure 2 is an enlarged perspective view of my improved traveler.

Figure 3 shows the traveler in section as mounted on a ring in section with the yarn extending through the traveler to the package.

Figure 4 is a view showing the ring in section and my traveler mounted thereon.

Figure 5 shows the traveler partially in section and mounted on a ring, a portion of which is shown.

It is found in practice that the old style traveler for handling the heavier yarns such as cord for cord tires and other heavy twisted yarns and the like is so out of balance when running that it has a tendency to swing or cant at an angle to the axis of the ring when running and so touch and scrape on the inside surface of the ring thereby removing the lubricant therefrom and so materially

increasing the dragging friction of the traveler which noticeably affects the quality of the yarn by stretching and destroying the elongation of the yarn and requires that the ring shall be much more frequently lubricated. To obviate these serious difficulties I have constructed a traveler which has a relatively straight shank portion to extend substantially in a straight line between the hook shaped end portions which engage the upper and the lower edges of the ring and I

have so constructed the shank portion of the traveler that it is of a width substantially less than that of either of its hook portions, by which construction it will be seen that in order to obtain the required weight of traveler I am enabled to extend the width and therefore increase the weight of both these top and bottom hook members. While running, the weight of the upper hook portion is carried by or supported on the yarn permitting the heavy lower hook portion to hang suspended from the yarn in a vertical position. In other words, by cutting away the stock of the shank portion I can proportionately increase the weight of the lower hook portion which increased weight will serve to cause the traveler to run in a vertical position while rapidly travelling about the ring. It will be seen that when the traveler is in a vertical position it does not tip or cant over and therefore the shank does not scrape the surface of the ring to remove the lubricant therefrom. In other words, by so constructing the traveler with a narrow shank and relatively wider and heavier lower portion, the suspension of the traveler on the yarn causes the traveler to float about the ring with the result that a much better and more uniform twist and elongation is obtained and this traveling is controlled by the added weight rather than by friction.

Also the working life of the traveler is increased and the lubricant is required to be applied much less often than when the old style of traveler is employed. The following is a detailed description of the present embodiment of my invention and showing one construction of traveler by which these advantageous results may be accomplished:

With reference to the drawings, 10 designates the usual twisting ring mounted in the rail 11 so that the axis thru its center will be vertical. A traveler used in a twisting machine for instance such as is employed to handle yarns in the form of a cord or other heavy twisted yarn used in the construction of so-called cord tires or shoes for motor vehicles, heavy ducks, etc., must be specially constructed for its work and in order that these travelers shall stand up under this heavy work and

function properly it is necessary that the traveler be so built or constructed as to hang substantially vertical, that is, to have its shank portion in substantial alignment with the axis thru the ring so as to substantially float about the ring when running up to speed and not swing off at an angle to this axis and so cramp its upper or its lower hook-shaped surfaces upon the edges of the ring, thus reducing the dragging friction to the minimum and nicely controlling the twisting and winding effects of the yarn or cord as led upon the package or spool and to accomplish this in a simple and effective way, I have formed the traveler with a shank portion 12 which is substantially straight, that is, it is not made in loop form and so is much less liable to tip and cramp and this shank portion serves to directly connect the upper hook-shaped end portion 13 and the lower hook-shaped end portion 14, which hook-shaped ends are adapted to engage the corresponding upper and lower edges of the ring 10. I preferably form this traveler from a ribbon of stock having a uniform thickness, the stock being preferably rounding or oval in cross section as at 15 on its inner surface so that when this rounding surface is in contact with the ring the contacting area will be reduced and so reduce to the minimum any scraping or abrading action that this carrier may have upon the ring when contacting with the same; also this rounding surface reduces the abrading action on the yarn as it is drawn thereover. I do not, however, limit myself to making the traveler with a rounded inner surface as this surface may be made flat, if desired.

It is also found to be of advantage to reduce the shank portion of the traveler throughout its length and to reduce this materially so that its width will be substantially less than that of the hook-shaped end portions. The purpose of this reduction is to reduce the weight and the frictional action of the traveler at its middle portion whereby in order to bring this traveler up to the required weight I am enabled to employ a heavier upper end 13 which is to be carried on the yarn and a substantially heavier lower end 14 which latter serves as a balancing weight to maintain the traveler in vertical position while running.

In some instances I may reduce the width of this shank to substantially one-third that of the hook end portions.

In some instances also it is found of advantage to offset the upper end of the shank portion as at 16 outwardly from the plane of the back of the shank to provide sufficient room for the travelling yarn.

In my improved traveler the yarn 17 rides across the upper portion of the narrow shank at the point 18 and the shank 12 sets substantially parallel with the inner surface of the ring and the weight of the lower hook end 14 is sufficient to hold the traveler in a substan-

tially upright position when running thereby preventing cramping and by being of the required weight this traveler floats on the yarn which is rapidly running through the same.

My improved traveler is preferably formed of a non-corrosive material such as bronze or the like and therefore does not require hardening.

This traveler is extremely simple and practical in construction and is effective in its operation and by its use much less lubricant is necessary on the rings owing to the reduction of both friction and heat and also by its use both the spindle speed and production may be materially increased and a better quality of yarn is produced over that obtained by the use of the old style traveler.

The foregoing description is directed solely towards the construction illustrated, but I desire it to be understood that I reserve the privilege of resorting to all the mechanical changes to which the device is susceptible, the invention being defined and limited only by the terms of the appended claims.

I claim—

1. A traveler for ring twisting adapted to run in a vertical position about its ring, the same comprising relatively wide hook-shaped end portions, and a relatively narrow and substantially straight shank portion connecting said wide end portions, the inner surface of said traveler being convex.

2. A traveler for ring twisting of uniform maximum thickness throughout its length adapted to run in a vertical position about its ring, the same comprising relatively wide hook-shaped end portions, and a relatively narrow and substantially straight shank portion connecting said wide end portions, the inner surface of said traveler being convex.

3. A traveler for ring twisting adapted to run in a vertical position about its ring, said traveler comprising relatively wide top and bottom hook-shaped end portions, and a relatively narrow straight shank portion connecting said end portions, that portion where the shank joins the top hook portion having an abrupt yarn guiding shoulder.

In testimony whereof I affix my signature.

AMOS MORIN.
